UNITED STATES PATENT OFFICE.

THOMAS DEMPSTER, JR., OF GRAND RAPIDS, MICHIGAN.

CLAMP FOR PRINTERS' FORMS.

1,073,221.

Specification of Letters Patent. Patented Sept. 16, 1913.

Application filed November 27, 1912. Serial No. 733,925.

To all whom it may concern:

Be it known that I, THOMAS DEMPSTER, Jr., a citizen of the United States, residing at Grand Rapids, in the county of Kent and State of Michigan, have invented certain new and useful Improvements in Clamps for Printers' Forms, of which the following is a specification.

My invention relates to improvements in clamps for printing forms, and its objects are: First, to provide a clamp with which the center of a type form may be held firmly from sagging without in any way subjecting the type to the danger of being marred by contact with the supporting element. Second, to protect the surface of the type form from being marred by direct contact with the metal surface of the clamp, and, third, to provide a clamp that will so secure a form of type that it may be readily carried from place to place without danger of being broken up. I attain these objects by the mechanism illustrated in the accompanying drawing, in which—

25 Figure 1 is an elevation of a type form with my appliance connected therewith. Fig. 2 is a plan of the same. Fig. 3 is a bottom plan of the clamp. Fig. 4 is a like view of one end of the small end of the clamp. Fig. 5 is an end elevation of the small end of the clamp with the center type support in position. Fig. 6 is a perspective of the center type support detached from the clamp, and made upon a large scale, and 35 Fig. 7 is a transverse section showing a square inner tube.

Similar letters refer to similar parts throughout the several views.

The body A of this clamp is made of 40 square tubing, and is provided with a slot a'' in the lower surface that the support F may slide freely in, and with a slot a' in the upper surface that the screw C may slide freely in, and with an arm a that is 45 designed to pass down upon the edge of the frame D, and is so arranged that the surface of the body A cannot come in contact with the ends of the type in the form.

The slide B may be made of a solid square 50 bar of metal, or of a square tube that will telescope perfectly into the tube or body A. This slide has an arm b, corresponding with the arm a and for the same purpose. This 55 slide is, also, provided with a slot, b', the upper end of which is made T form so the upper end and T formed head of the sup-

port F may be made to slide freely in said slot and the head f will hold the support securely in the slot so that great weight may be supported thereby without danger 60 of drawing the support F from its bearing in the slot b' b''. This slide is also provided with an opening c' that the head c of the bolt C may pass into and above the upper surface of the head f of the support 65 F, as the bolt is passed through its receiving hole in the slide B, as indicated in Fig. 5, so the support may be readily slid from end to end of the slot b' b'' without being obstructed by the head of said bolt. The 70 bolt C passes through the slot a' in the body tube A and is engaged by a thumb nut C' by means of which it may be secured to place with sufficient strength to render it impossible for the slide B to slip in the 75 body A. With this construction, it will be readily seen that the support F may be readily slid from one end to the other of the slot a'' for the purpose of adjusting it to a point as nearly central between the two 80 ends of the extended clamp as possible, and said support may be readily slid out of the end of the bar B and disconnected therefrom, as is plainly indicated in Fig. 5.

When applying this clamp to a type form 85 it is adjusted longitudinally to the exact length necessary to bring arms a, b, to bear snugly against the edges of the chase D and at the same time to take out a slug or type sufficient to allow the support F, (the 90 body of which is of the exact thickness of the type or slug to be removed,) when the keying up of the type form will spread the form and chase sufficiently to make the frame force heavily against the surfaces of 95 the arms a and b, and at the same time the adjacent type will be forced against the surface of the support with such force that it becomes almost impossible to draw the type off of the support, even though the 100 form may be of great weight.

While the clamp may be secured very firmly by means of a plain thumb screw or nut, as at C' in Fig. 1, I prefer that a serrated surface, as shown at a''' in Fig. 2, 105 be formed on the body A, and a corresponding square washer, as G, be placed between the surface of the body and the screw or nut C', as indicated.

To avert all possible danger of the metal 110 surface of the body A coming in contact with the letters on the type and marring

them I place a thin sheet of felt or other safe protecting element, as *e*, upon this surface, as indicated in Fig. 1.

In Fig. 7 I have shown the small end, *B'*, of the clamp made of square tubing and fitted to receive a support having a tapered or dovetailed head, as *f'* in lieu of the plain head, *f*, shown in Fig. 5.

C' in Fig. 4 indicates a round headed thumb nut that may be used in lieu of the winged thumb nut *C*, shown in Figs. 1 and 5, in cases where the latter would be likely to occupy too much space.

What I claim as new, and desire to secure by Letters Patent of the United States, is:

1. In a form clamp for printing forms, a square tubular body having a slot through the lower surface and the upper surface, a bar made to telescope into said body and having a T shaped slot in its lower surface, clamping arms projecting downward from one end of each of said parts, a securing bolt passed through the slot in the lower surface of the body and into the T shaped slot in the bar, said securing bolt having a T shaped upper end to engage the T shaped portion of said slot and a nut engaging said bolt to lock the body and the bar firmly together.

2. A clamp adapted to be used in connection with a printer's form, consisting of a tubular body having a slot through both its upper surface and its lower surface, a bar made to telescope into the body and having a T shaped slot in its lower surface, arms extending downward from one end of the body and of the bar, a T shaped supporting element fitted to slide freely in the T shaped slot in the bar and to extend downward through the slot in the body and into the form between rows of type and be there clamped to support the center of the form, and a bolt passing up through the bar and the upper slot in the body, and a nut for firmly holding the body and bar from longitudinal movement.

3. A clamp adapted to be used in connection with a printer's form, consisting of a tubular body having a slot through the upper and the lower sides, an arm projecting at right angles from one end, a bar made to telescope into the body and having a T shaped slot in the lower surface and an arm projecting at right angles from one

end, a T shaped supporting element made to slide freely in the T shaped slot and project downward through said slot and the slot in the body and project far enough to be engaged between two rows of type to support the center of the form, a bolt projecting from the bar up through the upper slot in the body, serrations formed on the upper surface of the body, a washer formed to engage said serrations, and a nut for securely fastening the body and bar together by engaging the bolt.

4. A clamp adapted to be used in connection with a printer's form, consisting of a tubular body having properly arranged slots through its upper and lower walls, an arm projecting at right angles from one end of the body, a bar fitted to telescope into the body and having a T shaped slot in its under surface, an arm projecting at right angles from one end of the bar, a supporting element fitted with a T shaped end to slide freely in the T shaped slot and to pass downward into the form and be clamped between two rows of type to support the center of the form, a bolt passing upward through the bar and the slot in the upper wall of the body, a nut engaging said bolt to secure the body and the bar firmly together, and a pliable coating on the lower surface of the body.

5. In a clamp for printer's forms, a body having a slot through both the upper and the lower walls, an arm at right angles with one end of the body, a bar telescoping into the body and having a T shaped slot in one surface, an arm at right angles with one end of the bar, a supporting element having a T shaped head arranged to slide freely in the T shaped slot and project downward to be engaged in the form, a single bolt passing through the slot in the body of the bar and a nut for securing the body and bar together, serrations formed in the upper surface of the body, a washer formed to lie between the nut and said serrated upper surface, and a pliable coating on the lower surface of the body each side of the slot.

Signed at Grand Rapids Michigan November 15, 1912.

THOMAS DEMPSTER, JR.
